(57) **CLAIM**

The ornamental design for a gantry of combined positron emission tomography and computed tomography, as shown and described.

DESCRIPTION

FIG. 1 is a front perspective view of a gantry of combined positron emission tomography and computed tomography showing our new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof; and,

FIG. 7 is a top plan view thereof.

The bottom plan view is omitted.
